PHONOGRAPH CARTRIDGE

Clarence F. Jensen, 124 Morningside Ave., Lombard, Ill.

Filed Aug. 12, 1960, Ser. No. 61,730

Term of patent 14 years

(Cl. D26—14)

FIGURE 1 is a perspective view of a phonograph cartridge showing my new design;

FIGURE 2 is a plan view of one side thereof;

FIGURE 3 is a plan view of the top side thereof;

FIGURE 4 is a plan view of the side opposite FIG. 2;

FIGURE 5 is a front end elevational view; and

FIGURE 6 is a rear end elevational view with the cartridge having one side facing upwardly as in FIGS. 2 and 5.

I claim:

The ornamental design for a phonograph cartridge, as shown and described.
